(57) **CLAIM**

The ornamental design for an exercise apparatus, as shown and described.

DESCRIPTION

FIG. 1 is a perspective view of an exercise apparatus showing our new design;

FIG. 2 is a front view of the design of FIG. 1;

FIG. 3 is a back view of the design of FIG. 1;

FIG. 4 is a top view of the design of FIG. 1;

FIG. 5 is a bottom view of the design of FIG. 1;

FIG. 6 is a first side view of the design of FIG. 1; and,

FIG. 7 is a second side view of the design of FIG. 1.

The broken lines shown in the figures are for the purpose of illustrating portions of the exercise apparatus, which form no part of the claimed design.

The broken lines on the strap show the boundary of the design. The broken lines and the appearance of any portion beyond the broken lines form no part of the claimed design.
